UNITED STATES PATENT OFFICE.

GEORGE A. KELLEY, OF JOPLIN, MISSOURI.

GRADER-FRAME.

1,127,774.

Specification of Letters Patent.

Patented Feb. 9, 1915.

Application filed March 6, 1913. Serial No. 752,470.

To all whom it may concern:

Be it known that I, GEORGE A. KELLEY, a citizen of the United States, residing at Joplin, in the county of Jasper, State of Missouri, have invented certain new and useful Improvements in Grader-Frames; and I do hereby declare the following to be a full, clear, and exact description of the invention, such as will enable others skilled in the art to which it appertains to make and use the same.

The present invention relates to certain novel and useful improvements in sand graders.

15 In carrying out my invention it is my purpose to provide a grader embodying in its construction a plurality of screens whereby either gravel or fine sand may be sifted.

A further object of the invention is the 20 provision of a grader having a removable sand screen so that when it is desired to grade sand or gravel of such coarseness that it would not pass through the removable screen the latter may be dispensed with and 25 the sifting or screening carried on by means of a second screen permanently fixed in the grader frame.

With the above recited objects and others 30 of a similar nature in view, my invention consists in the construction, combination and arrangement of parts set forth in and falling within the scope of the appended claim.

In the accompanying drawings, Figure 1 is a front view of a grader in position for 35 and adapted to screen gravel, the sand screen being removed. Fig. 2 is a view in elevation of the removable sand screen. Fig. 3 is a view in side elevation of a grader embodying the invention. Fig. 4 is a vertical 40 longitudinal sectional view taken through the grader with the removable or sand screen in place. Fig. 5 is a transverse sectional view taken through the grader with the two screens in position. Fig. 6 is a perspective 45 view of the brace leg.

In the present instance I have shown and described a grader embodying among other features a frame adapted to be supported in a vertically inclined position 50 through the medium of a pivoted brace leg. This grader is provided with a plurality of screens, one of which being a relatively coarse screen is permanently attached to or fixed in the frame and is adapted especially 55 for screening gravel. When it is desired to screen fine sand, instead of resorting to

the use of a separate grader, I provide a removable screen of fine mesh which is designed to be placed in the grader frame across the face of the coarse screen, and held 60 spaced apart therefrom so that the sand may be thrown against and screened by means of the fine mesh.

Referring now to the accompanying drawings in detail, the letter A indicates the 65 grader frame as an entirety, the latter comprising the longitudinal side walls 1—1, the top wall 2 and the bottom wall or sand board 3. It will be seen that the top wall is substantially equal in height to the height 70 of the side walls and forms an inclosure between the same, while the bottom or sand board forms a chute or guideway in conjunction with the adjacent portion of the side walls. Attached to the rear longitudinal edges of the side walls are the strips 4 which project inward of such side walls so as to form flanges, while 5 indicates a similar strip attached to the back edge of the top wall and extending inward to form a 75 flange which lies between the side strips or flanges 4—4. Similarly a strip 6 is fastened to the upper back portion of the sand board and forms a flange extending between the lower end portions of the side strips or 80 flanges 4—4. Permanently fastened to the back of this frame is a gravel screen 9 which is formed of relatively large mesh, and in the present instance I construct this screen of a series of longitudinally extending parallel 85 wires 7, which have their upper terminals secured as at 8 to the back of the strip 5 while their lower terminals are fastened as at 9 to the back of the bottom strip 6. These longitudinal wires are in turn crossed by a 90 series of transverse wires 10 which have their terminals secured in the back of the side strips 4—4 as at 11. It is to be understood that this gravel screen may be of any 95 coarseness or size of mesh to suit particular 100 conditions, and the mesh may be constructed and secured in any desired manner.

The brace leg for supporting the grader frame consists of a pair of parallel bars 12—12 which are pivoted at their upper ends 105 as at 13 to opposite upper end portions of the screen frame. The rear longitudinal edges of each of these bars is provided with a flange strip 14 which terminates short of the pivot point of the bar to which it is 110 attached as is shown at 15. These flange strips for the leg are so arranged, that when

the latter is moved parallel to the grader frame or to its closed position they will abut against the rear of such frame and form stops for the leg.

5 The numeral 16 indicates a transverse brace bar connecting the flanges 14 at their top portions while 17 indicates a similar brace bar at the lower portion of the leg. These two bars tend to strengthen and brace 10 the supporting leg of the grader frame. The lower end of each leg is preferably beveled or reduced as at 17', and is provided with a spike or sharpened stud 18 for penetrating the ground and anchoring the grader firmly 15 in position. In order to limit the outward movement or throw of the brace leg I provide at the top of the screen frame a stop bar 19 while 20 designates a tie chain having one end connected to the ring 21 carried 20 by the metallic cross rod or wire 22, the opposite end of said chain being connected to the staple or eye 23 on the lower cross bar 17.

When it is desired to screen coarse sand 25 mixed with gravel, or gravel alone, the structure just described as embodying the permanent screen is employed in the well known manner. When, however, it is the purpose to screen sand such as is used for 30 mortar and similar purposes, I make use of the removable sand screen *s* which is shown in detail in Fig. 2. This screen comprises an approximately rectangular unitary frame 24 formed of iron piping or rod. This 35 frame is covered with a screen 25 of relatively fine mesh. This removable screen is further braced by means of the long wire 26 and the cross wires 27. When it is intended to use this removable screen, the latter is placed in the grader frame over and 40 in front of the coarse screen so that when in operative position its rectangle rests against the side strips or flanges 4—4 and the top and bottom strips or flanges 5 and 45 6 of the grader frame. Thus the screen while securely supported will be held spaced apart from the coarse screen the width of the flanges upon which it rests. It will of course be evident that when the sand to be 50 screened is thrown up against the fine mesh it will pass therethrough and through the coarse mesh, the gravel or other material

screened out from the sand dropping down on the sand board to the ground. The frame of the fine screen *s* should be of such size 55 and construction as to snugly and tightly fit within the grader frame and in order that it may be readily removed therefrom a small pulling chain or cord 27 may be attached to one of the transverse sides of the frame 24 60 for this purpose. It will be seen that when both the screens are used, the device performs the function of a grader, for when the material to be screened is thrown thereagainst the finer particles will pass through 65 these screens, while the coarser particles will be caught by the fine screen and directed down to the sand board. This device will be found especially adapted for use in screening sand and gravel such as is employed 70 in building operations, the manufacture of mortar and other similar purposes.

While I have herein shown and described one particular embodiment of my invention I wish it to be understood that I do not 75 confine myself to all the precise details of construction herein set forth by way of illustration, as modification and variation may be made without departing from the spirit of the invention or exceeding the scope of 80 the appended claim.

What I claim is:

In an apparatus of the class described, the combination with a frame including side walls, a top wall, and a bottom board, of 85 flanges at the rear of the frame and extending inward thereof, a relatively coarse screen permanently attached to the rear of the flanges, a relatively fine removable screen located within the frame and adapted to 90 rest on the front faces of the flanges and to be held spaced apart from the coarse screen by such flanges, said fine screen being confined against longitudinal movement by the top wall and the bottom board and against 95 lateral movement by the side walls of the frame, and a support for the frame.

In testimony whereof, I affix my signature, in the presence of two witnesses.

GEORGE A. KELLEY.
